UNITED STATES PATENT OFFICE.

FRIEDRICH WILHELM OEBURG, OF NEW YORK, N. Y.

WAGON-BRAKE.

SPECIFICATION forming part of Letters Patent No. 423,695, dated March 18, 1890.

Application filed January 18, 1890. Serial No. 337,377. (No model.)

To all whom it may concern:

Be it known that I, FRIEDRICH WILHELM OEBURG, of New York city, New York, have invented an Improved Wagon-Brake, of which 5 the following is a specification.

This invention relates to a wagon-brake that will automatically lock the hind wheels as soon as the horses are pulled back.

It consists in the various features of improvement more fully pointed out in the 10 claims.

In the accompanying drawings, Figure 1 is a vertical longitudinal section of a wagon provided with my improved brake on line xx , 15 Fig. 2. Fig. 2 is a bottom view thereof; Fig. 3, a vertical longitudinal section on line yy , Fig. 2; Fig. 4, a vertical transverse section on line zz , Fig. 2; Fig. 5, a rear view of the rear axle, showing one of the clutches in section. 20 Fig. 6 is an end view of one of the clutches with the wheel removed, and Fig. 7 is a top view of ring a^4 .

The letter a represents a sliding bar placed below the reach a' of a wagon, and guided 25 by a clip a^2 . At its forward end the bar a terminates in a circular plate a^4 , having a long and narrow central slit or eye. Through the plate a^4 passes the king-bolt b , and thus it will be seen that, though the bar is secured in 30 place, it is free to slide backward and forward.

Around the rim of circular plate a^4 there is placed an annular plate c , which is free to revolve around plate a^4 . To the plate c the horses are hitched by an arm c' , carrying the 35 coupling c^3 for the tongue or thill. To the annular plate c may also be secured the lower segment of the fifth-wheel c^8 . The pull of the horses, whether directly in front of the vehicle or turned to the side, will, by the annular 40 plate c , be transmitted to rod a to draw the same forward. The rear end of rod a is connected to the clutch mechanism that engages the hind wheels, and which is of the following description: Beneath the rear axle d are 45 guided, by means of clips d' , the brake-rods d^2 , carrying clutches or brakes d^3 , that engage corresponding surfaces on the hubs d^4 . At the inner ends the brake-rods are separated by a strong spring d^5 , coiled around a pin d^6 , 50 that enters the ends of the rods d^2 , to stiffen the structure. The rods d^2 are connected to

the sliding bar a by means of a pair of levers d^7 , pivoted at one end to the rods and joined at the other end to the bar by a strong wire or link d^8 . When the horses pull forward, 55 the bar a will be drawn forward and the rods d^2 will be drawn toward each other by levers d^7 , against the action of spring d^5 , to take off the clutch or brake. As soon, however, as the horses are pulled back, the annular plate c 60 will no longer draw bar a forward, and the spring d^5 will force the rear ends of rods d^2 asunder, thus at the same time pulling bar a backward and putting on the brakes.

In order to permit the brakes to be put on 65 or taken off at will by the driver, I have devised the following construction: Into the slit of the circular plate a^4 enter two conical noses $e e'$, one engaging the forward end of the slit and the other the backward end thereof. In 70 order to guide the noses into the slit, the upper face of the plate a^4 is provided with the tapering projections a^6 , Fig. 3. The noses $e e'$ are connected to the rods $f f'$, respectively, reaching into the wagon-body, where 75 they are provided with the treads $g g'$. Each rod is retained in its raised position by a coiled spring $h h'$. If the driver presses upon treadle g , he will cause the nose e to engage the forward end of the plate a^4 , and he 80 will thus draw the rod a forward and take off the brakes. If the driver presses upon treadle g' , he will cause the nose e' to engage the rear end of the plate a^4 , and will thus push or retain the rod a in its backward position, to put 85 on or close the brakes. A pair of catches $i i$, pivoted to the bolster j or to any other part of the wagon, serve to hold the noses $e e'$ in engagement with the plate a^4 when such noses are depressed. In this way the brakes can be 90 either applied or taken off for any length of time.

What I claim is—

1. The combination of a wagon with a sliding bar having circular plate a^4 , an annular 95 plate c , surrounding plate a^4 and carrying the shaft-coupling, and with a brake-controlling mechanism connected to the sliding bar, substantially as specified.

2. The combination of a wagon with a sliding bar having slotted plate a^4 , an annular plate c , surrounding plate a^4 and carrying the 100

shaft-coupling, a nose engaging the slitted plate, and a brake-controlling mechanism connected to the sliding bar, substantially as specified.

5 3. The combination of a wagon with a sliding bar having slitted plate a^4 , a surrounding annular plate c , carrying the shaft-coupling, a nose engaging plate a^4 and connected to a

foot-rod, a catch for locking the nose, and a brake-controlling mechanism connected to the 10 sliding bar, substantially as specified.

FRIEDRICH WILHELM OEBURG.
